DRAWING BOARD AND THE LIKE

Tallmon Ethan Horst, Chicago, Ill.

Application April 26, 1930, Serial No. 447,557
Renewed May 22, 1933

16 Claims. (Cl. 45—131)

The present invention has to do with an improved construction of drawing boards and the like. The construction herein disclosed is so arranged that it can be folded up into a relatively small compact structure and when so folded up into such structure it serves to establish and provide a carrying case for painter's or draftsmen's equipment or equipment of that kind. In other words, the device is so constructed that it can be folded up into a box-like receptacle or can be opened out into a flat drafting board.

Another feature of the invention relates to the provision of an improved hinge structure for joining the sections together so that they will come into the proper relative positions when either folded up or opened out. It is a further object to so arrange this hinge structure that it will effectively lock the companion board sections rigidly with respect to each other so that when opened out into the drafting board form the device will be sufficiently rigid for ordinary drafting operations.

Another feature of the invention relates to the provision of a series of panels so related and hinged together that when folded up into the box structure they provide a box of convenient proportions; and when opened out into the drafting board structure they provide a drafting board of uniform thickness at all points; the panels coming into such relationship that this result is accomplished.

Another object is to provide a device of very simple form and few parts and one which can be readily manufactured at low cost.

Other objects and uses of the invention will appear from a detailed description of the same which consists in the features of construction and combinations of parts hereinafter described and claimed.

In the drawings:

Figure 1 shows a perspective view of the device folded up into box form showing the relation which is then assumed by the different panels;

Figure 2 shows a view of the device opened out into the flat drafting board form, certain of the panels being in a partially raised position;

Figure 3 shows a fragmentary longitudinal section taken through the central panel and the adjacent edge portions of the side panels, the parts being opened out into the drafting board position and the end panel being folded over into the drafting board position;

Figure 4 shows a view similar to that of Figure 3 but with the panels turned into a quarter

turn, with the exception that the end panel has been turned only part way around so that the locking function has just commenced;

Figure 5 shows a view similar to Figure 4, with the exception that side panels have been turned up at right angles to the plane of the bottom panel, and the end panel has been turned up into its working position;

Figure 6 shows a fragmentary section on the line 6—6 of Figure 4, looking in the direction of the arrows, the end panel being shown in one position by full lines and in two other positions by dotted lines;

Fig. 7 shows a perspective view of the bracket to which the cam shaft and cams are pivoted; and

Fig. 8 shows a fragmentary detail view of one of the cams, being taken on the line 8—8 of Figure 5, looking in the direction of the arrows.

The device herein illustrated includes the side panels 9 and 10, bottom panel 11, end panels 12 and 13, and top panels 14 and 15. The bottom panel 11 and the side panels 12 and 13 as well as the top panels 14 and 15 are each of less thickness than the side panels 9 and 10. In fact the thickness of the bottom panel 11 plus the end panel 13 and the top panel 15, or the thickness of the bottom panel 11 plus the end panel 12 and the top panel 14 is equal to the thickness of either of the side panels 9 and 10, both of said side panels being of the same thickness. Furthermore, the combined lengths of the top panels 14 and 15 are equal to the length of each of the side panels 9 and 10, so that the two top panels 14 and 15 together establish the entire length of the device. Furthermore, the end panels 12 and 13 are each substantially equal in length to the corresponding top panels 14 and 15. From this it follows that the height of the box structure is one-half of its length—that is to say, the width of each of the side panels 9 and 10 is equal to one-half its length.

The adjoining edges of the panels 12 and 14 are hinged together along the line 16 and the adjoining edges of the panels 13 and 15 are hinged together along the line 17. These hinges 16 and 17 permit the panels 13 and 15 to be folded around to bring their two outside faces into face contact with each other. This is also true with respect to the panels 12 and 14. When the two panels of each of said pairs are folded into face contact, they may then be turned down into face contact with the bottom panel 11. This condition being illustrated with respect to the panel 14 (and the hidden panel 12) in Figure 2. Due to the rela-

tive thicknesses of the parts, they will, when folded into this position, establish a combined thickness to bring their exposed faces flush with the exposed faces of the panels 9 and 10, such condition being illustrated with respect to the panel 14 in Figure 2. Due to this circumstance, the entire surface of the drafting board will present a flush continuous substantially smooth surface.

- 10 The side panels 9 and 10 are hinged with respect to the panel 11 so that they can either be opened out into the flat position of Figure 2 or they can be folded up into the right angular position of Figure 1. The hinge structures by which this 15 result is accomplished are also of such a nature that when the side panels 9 and 10 are opened out parallel to the bottom panel 11 and the end panels 12 and 13 are folded down against the bottom panel 11, the parts are locked so that the side 20 panels 9 and 10 are retained in their condition of parallelism with respect to the bottom panel 11. The hinges 18 and 19 are for accomplishing the above purposes. I will now describe the construction of these hinges in detail. For this purpose only one of the hinges need be considered, as they are both of the same construction, and reference may be had to Figures 2 to 8, inclusive.

Each end portion of each of the side panels 9 and 10 is provided adjacent to the bottom panel 30 11, with a pocket or recess. These are the pockets 20 and 21, respectively. Each hinge includes a box structure 22 which constitutes in effect one of the end portions of the bottom panel 11; and the box structures 22 of the bottom panel 11 are 35 lined up with the corresponding pockets 20 and 21 respectively. The inner edges of the side panels 9 and 10 are directly connected to the hinge structure by links 23 and 24 (see Figures 4 and 5) one end of each of said links being pivotally connected 40 to the upper face portion of the corresponding side panel and the other end of each link being pivotally connected to the upper face portion of the hinge. The relationship is such that when the side panels lay out parallel to the bottom 45 panel the links 23 and 24 compel the top surfaces of the side panels to come flush with the top surfaces of the box structures 22; whereas when the side panels are turned to the right angle position of Figure 5, the links are of such length that 50 they allow the edges of the side panels to drop down to a position flush with the bottom surface of the bottom panel, and in so doing they draw the side panels inwardly so as to bring their top faces into flat contact with the ends of the hinges. 55 This result is clearly shown in Figure 5.

For the above purpose I prefer to provide the brackets 25 and 26 on the edge portions of the side panels, said brackets being offset as shown in Figure 3, and the adjacent ends of the links 23 and 24 are pivotally connected to said brackets by the pins or rivets 27 and 28, respectively.

Likewise, I prefer to provide brackets 29 and 30 on the edge portions of the hinge structures, the inner ends of the links 23 and 24 being pivotally connected thereto by the pins or rivets 31 and 32.

There are also provided other links 33 and 34 which have their outer ends pivotally connected to the edge portions of the side panels 9 and 10, 70 by the pins or rivets 35 and 36 respectively. These links 33 and 34 reach over into the hinge structure and are slidably mounted therein, for which purpose they slide through the brackets 29 and 30 already referred to. Such fact is clearly evident from Figure 3. The inner ends of the links

33 and 34 are provided with hooks 37 and 38 (best shown in Figure 3); and due to the manner in which the links themselves are slidably supported, these inner hook ends 37 and 38 are of a spring nature so that in case of necessity they can spring down slightly. 80

There is a bracket 39 located in the central portion of each of the hinges. These brackets are of peculiar form including the downwardly extending arms 40 and 41, which then reach outwardly in the projections 42 and 43. The position of one of these brackets in its hinge is well shown in the section of Figure 6. There is a short shaft 44 journaled in the extensions 42 and 43. The central portion of this shaft has rigidly connected to it an arm 45 to which the corresponding end panel 12 or 13 as the case may be is connected as shown in Figure 2 in particular. Consequently, the swinging of the end panel rotates the shaft. 85

The shaft 44 is provided with a pair of segmental cams 46 and 47 which are adapted to engage and pull upon the corresponding hooks 37 and 38. This relationship is clearly shown in Figure 3. 90

It will now be evident that by turning the side 100 panels 9 and 10 out parallel to the bottom panel 11, the links 33 and 34 are projected inwards towards each other so as to carry their hooks 37 and 38 into position adjacent to the cams 46 and 47. Thereupon, by turning the end panel 12 or 13 to 105 bring the same flush against the bottom panel 11, the cams pull upon the hooks so as to draw the links 33 and 34 up tight with the result that the side panels are firmly locked in the extended or parallel position. This is essential in order to be 110 able to satisfactorily use the drafting board.

The operation and use of this device in service will now be quite evident. Assuming that the parts have been turned out into the drafting board position, and assuming that it is desired to 115 fold them around into the box form, the double panels 12-14 and 13-15 are folded around so that the panels 12 and 13 lie at right angles to the bottom panel 11. During this operation the panels 12 and 13 are turned through three-quarters 120 of a turn from the horizontal dotted line position of Figure 6, through the full line position, and up into the vertical dotted line position of Figure 6. This action causes a sufficient rotation of the shafts 44 to completely unlock the 125 hooks 37 and 38. This result having been accomplished, the side panels 9 and 10 are turned up into the enclosing position of Figure 1. The top panels 14 and 15 may then be folded out into the horizontal or closing position indicated in Figure 130 1. This will complete the enclosure of the device 135 as a box or carrier. If desired, suitable handles may be provided for carrying the device when opened into the box form. These may be in the form of wire loops, such as 48 and 49, which slide 140 down into the body portion of the panels when not in use.

While I have herein shown and described only a single embodiment of the features of my present invention, still I do not intend to limit myself thereto, except as I may do so in the claims.

I claim:

- In a device of the class described, the combination of a pair of side panels, a bottom panel, end panels having their lower ends hingedly connected to the ends of the bottom panel, top panels having their ends hingedly connected to the free ends of the end panels, and hinge connections between the side panels and the bottom panel, the side panels being substantially twice as long as

they are broad, and each end panel and each top panel being of length equal to the breadth of a side panel, substantially as described.

2. In a device of the class described, the combination of a pair of side panels, a bottom panel, end panels, hinge connections between the outer ends of the end panels and the corresponding ends of the bottom panel, and a top panel having its end hingedly connected to the free end of one of the end panels, and hinge connections between the side panels and the bottom panel, each side panel being substantially twice as long as it is broad and each end panel having a length equal to the breadth of a side panel, substantially as described.

3. In a device of the class described, the combination of a pair of side panels, a bottom panel located between the edges of the side panels, hinge connections between the side panels and the bottom panel permitting the side panels to be folded into parallelism with the bottom panel or at right angles with respect to the bottom panel, end panels, hinge connections between the ends of the end panels and the ends of the bottom panel, top panels, hinge connections between the ends of the top panels and the free ends of the end panels, the bottom panel, end panels and top panels all being of the same width, the side panels being substantially twice as long as they are broad, and the end panels and top panels being of a length equal to the breadth of the side panels, the combined thickness of the bottom panel and either end panel together with the adjoining top panel being equal to the thickness of a side panel, substantially as described.

4. In a device of the class described, the combination of a pair of side panels, an intermediate bottom panel, end panels, hinge connections between the ends of the end panels and the ends of the bottom panel, top panels, hinge connections between the ends of the top panels and the free ends of the end panels, and hinge connections between the side panels and the bottom panel, including means for locking the side panels and the bottom panel in co-planar relationship when the end and top panels are folded over adjacent to the bottom panel, substantially as described.

5. In a device of the class described, the combination of a pair of side panels, an intermediate bottom panel, hinge connections between the side panels and the bottom panel, end panels, hinge connections between the end panels and the ends of the bottom panel, and means under the control of said last mentioned hinge connections operative effectively to lock the side panels in position parallel to the bottom panel when the end panels are folded into position adjacent to the bottom panel, substantially as described.

6. In a device of the class described, the combination of a central panel and two adjacent side panels, together with means for hinging the adjacent edges of the side panels to the central panel, said hinge means being located adjacent to the top surfaces of the panels, links pivotally connected to the side panels adjacent to their bottom surfaces and slidably towards and from each other adjacent to the central panel, a cam shaft journaled in the central panel, hooks on the inner ends of said links, segmental cams on the cam shaft in position to engage said hooks for the purpose of drawing the links towards each other, and means for turning said shaft effectively to rotate the cams and draw the links towards each other, substantially as described.

7. In a device of the class described, the com-

bination of a central panel and a pair of side panels adjacent to the edges thereof, means for hingedly connecting the side panels to the central panel adjacent to the top surfaces of said panels, links pivotally connected to the side panels adjacent to their bottom surfaces, said links being movable towards and from each other adjacent to the bottom surface of the central panel, and means under control of the operator for drawing the links towards each other to lock the side panels in co-planar relationship with respect to each other and with respect to the central panel, substantially as described.

8. In a device of the class described, the combination of a pair of panels having a substantial thickness, links pivotally connecting said panels together, said links being located adjacent to the top surfaces of the panels, and said links being positioned to establish connection between the panels when their edges are in contact and the surfaces of the panels are flush with each other, and the arrangement being such that the panels may be turned into right-angular relationship with respect to each other with the edge portion of one panel in contact with the surface of the other panel, together with means for drawing the edge portions of the panels together when the panels are in co-planar relationship, substantially as described.

9. In a device of the class described, the combination of a pair of side panels, an intermediate bottom panel of less thickness than the side panels, hinge connections between the side panels and the bottom panel, end panels, hinge connections between the ends of the end panels and the adjacent ends of the bottom panel, top panels corresponding to the respective end panels, the combined thickness of a top and end panel being substantially equal to the difference between the thickness of the bottom panel and a side panel, hinge connections between the top panels and the free ends of the corresponding end panels, the arrangement being such that the end and top panels may fold down adjacent to the bottom panel and between the side panels so that the exposed surfaces of the end and top panel pairs are flush with the top surfaces of the side panels, substantially as described.

10. In a device of the class described, the combination of a central panel together with a pair of side panels adjacent thereto, all of said panels having a substantial thickness, pivotal hinge connections between the adjacent edges of the side panels and the central panel close to the top surfaces of said panels, together with means under control of the operator operative to draw the side panels towards the central panel by exerting tension on the lower surface portions of the side panels when the panels are in substantial parallelism with respect to each other, whereby all of said panels are locked in co-planar relationship, substantially as described.

11. In a device of the class described, the combination of two panels, each having a substantial thickness, pivotal hinge connections between the adjacent edges of said panels close to the top surfaces of the panels, together with means under the control of the operator operative effectively to draw the two panels together by exerting tension on said panels, whereby the panels are locked in co-planar relationship, substantially as described.

12. In a device of the class described, the combination of a central panel together with a pair of side panels adjacent thereto, all of said panels

having a substantial thickness, together with means operative to draw the side panels towards the central panel by exerting tension on the side panels when the panels are in substantial parallelism with respect to each other, whereby all of said panels are locked in co-planar relationship, substantially as described.

13. In combination, two panels pivotally interconnected by means of a pair of links, said links being pivotally affixed to one of said panels, and one link of each pair of links being pivotally affixed to the other of said panels, and a slidable connection between the other link of said pair of links and the second mentioned panel permitting sliding movement only with the sliding link lying parallel to said second mentioned panel, substantially as described.

14. In combination, two panels pivotally connected together by means of hinges, each of said hinges being composed of a plurality of links, each of said links being pivotally connected at one end to one panel, and some of said links being pivotally connected at the other end to the other panel and some of said links being slidably connected at said last mentioned end to said other panel to permit sliding movement only with said sliding links travelling parallel to said panel, substantially as described.

15. In combination; two panels pivotally connected together by means of a pair of links, one of said links being pivotally connected at one end to one panel and at the other end to the other panel, said pivotal connections being adjacent to one surface of each of said panels, and the other of said links being pivotally connected at one end to one panel and slidably connected at the other end to the other panel, said pivotal and slide connections of said second mentioned link lying adjacent to the opposite surface of said panels from that of the first mentioned link, substantially as described.

16. In combination, a hinge comprising a link pivotally connected at one end adjacent to a surface of one panel and at the other end adjacent to the corresponding surface of a second panel, a second link pivotally connected adjacent to the other surface of the first mentioned panel opposite the connection of the first mentioned link, and slidably connected adjacent to the other surface of the second mentioned panel opposite to the connection of the first mentioned link on said panel and having sliding movement only with said sliding link moving parallel to said panel, substantially as described.
